UNITED STATES PATENT OFFICE.

WALTER BLACK, OF CHICAGO, ILLINOIS.

MORTISING-MACHINE.

SPECIFICATION forming part of Letters Patent No. 605,774, dated June 14, 1898.

Application filed May 29, 1897. Serial No. 638,717. (No model.)

To all whom it may concern:

Be it known that I, WALTER BLACK, a citizen of the United States, residing at Chicago, in the county of Cook and State of Illinois, 5 have invented certain new and useful Improvements in Mortising-Machines, of which the following is a specification.

My invention relates to that class of machinery which is known as "mortising machinery" and which is used for the purpose of boring or removing material so as to form a substantially rectangular recess in a plank, board, or similar object; and the object of my invention is to provide a simple, economical, 15 and efficient machine for cutting or boring rectangular or square holes in timbers, planks, boards, or similar objects.

The invention consists in the features, combinations, and details of construction hereinafter described and claimed.

In the accompanying drawings, Figure 1 is a plan view, looking at it from the top, of one form of machine constructed in accordance with my improvements; Fig. 2, a sectional elevation, taken on line 2 of Fig. 1, when the parts are arranged in a straight line across the bed of the machine; Fig. 3, a sectional elevation of a portion of a machine, taken on line 3 of Fig. 2; Fig. 4, a sectional view of a 25 portion of a machine, taken on line 4 of Fig. 1; and Fig. 5, an enlarged detail of the oscillating cutting-tool, as hereinafter described.

In the art to which this invention relates it is well known that the forming of a rectangular recess or what is known as a "square hole" in a piece of wood, plank, or similar object is very difficult and expensive and that a large number of machines have been designed, some of which have been patented, 35 for the purpose of making such a recess. There are various objections existing in this class of machines, either because of the reason that the bottom of the recess is not substantially square with its side walls or that some 40 preliminary steps must be taken before the piece can be operated on. My invention is intended to remove these objections by providing a simple, economical, and efficient machine which is capable of boring, in the 45 true sense of the word, a square hole of any desired length and depth and forming the

bottom portion substantially at right angles to the side of the end walls of the recess.

In constructing a machine in accordance with my improvements I make a main bed 55 A of the desired size, shape, and strength to hold the operative parts. Upon this bed I mount two reciprocating slides B and B', having racks b and b', engaged by a central oscillating gear C, which is made, preferably, in 60 the form of a double segment, though this form is immaterial, as it may be a plain spur-gear. To each of these slides are secured cutters D and D' in any convenient manner, and which project a considerable distance 65 beyond the slides for the purpose of engaging and operating on the piece of timber M, as shown in Fig. 1. These reciprocating cutters are made in the shape of a straight plane on their outer sides and provided with ratchet-shaped cutting edges d on their inner sides for the purpose of cutting and pulling the shavings out of the cut, and thereby prevent 70 clogging. These reciprocating cutters are worked alternately, first cutting into the material at one end of the recess and then at the other end of the recess to the depth of a shaving, the material being fed to the cutters in the desired manner at each stroke.

To form the bottom of the recess and remove the bulk of the material, I provide what I term a "vibrating" or "oscillating" cutter E, which has its point or cutter proper, E', pivotally secured thereto at e. The main body of the cutter is mounted in a pivotal or 85 swinging holder G, independently mounted and which has a slotted arm g extending to the rear thereof and adapted to be engaged by a bolt g' in the lever-arm H, which lever-arm also operates the oscillating gear. It will 90 thus be seen that the throw of the cutter lever-arm H being constant the movements of the reciprocating cutters are always the same, while the position of the engaging bolt g', which secures the slotted arm of the oscillating cutter-holder to the lever-arm, governs 95 the vibrations of the oscillating or vibrating cutter. For instance, when it is desired to cut a hole in the material as long as possible the reciprocating cutters D and D' are moved 100 over in their holding portions b³ of the reciprocating slides as far as possible, and the en-

gaging bolt is slid along in the slotted arm *g* and the slot *h* on the lever-arm the proper distance from the pivotal center of both of such parts, so as to obtain the desired relative 5 swing of the cutting edge of the vibrating cutter.

To operate the oscillating gear and also the other parts above described, a main driving-shaft *I* is provided at one end of the machine, 10 having a crank *i*, which is connected to a slide *I'* by means of a connecting-rod *i'* and in turn, by means of a connecting-rod *I²*, with the lever-arm *H*, so that the rotations of the driving-shaft *I* impart the desired reciprocating and 15 vibratory motions to the cutters.

To feed the plank or board into contact with the cutters when desired, an adjustable table *K* is provided, having a saddle portion *k*, mounted on suitable vertical ways *k'*, the 20 vertical position being secured by means of an adjusting-screw *K'*. A second slide *L* is provided, which has a movement in the direction toward and away from the cutters and provided with a feed-screw *l* and clamp *L'*, 25 which is used to hold the board in position, as shown in Figs. 1 and 2, so that it may be fed into engagement with the cutters or removed therefrom, as desired.

The operation of the machine is as follows: 30 The board or plank is placed in position, as shown in Figs. 1 and 2, so that the extreme cutting edges of the reciprocating cutters will mark or cut into the exposed side of the piece the depth of a shaving. The machine is 35 started and the reciprocations bring the cutters *D* and *D'* into contact with the material alternately and cut into the same the desired width and depth of one shaving. The vibratory motion being imparted to the cutter *E* 40 and operating it at right angles to the reciprocating cutters, its cutting edge *e'* digs into the material and removes one shaving to form a preliminary depth of the cut. It then moves in the opposite direction, and its opposite cutting edge, which might be *e²*, is tilted, so as 45 to cut the other extreme of the throw, or just far enough to meet the cut of the reciprocating cutter, thus forming a new depth of cut. The board is then fed toward the cutter by 50 means of the feed-screw *l* the depth of another cut. The reciprocating cutters mark another shaving, which in turn is cut away by the vibrating cutter, these cuts continuing until the recess *m* in the plank *M* is at the desired 55 depth. In Fig. 1 it will be seen that the cutter *D'* has just marked the depth of a shaving. The vibrating or oscillating cutter is prepared to make a vibration, with its cutting edge *e'* prepared to dig into the wood—that 60 is, it will vibrate from the position shown in Fig. 1, so that its opposite end will be removed from contact with the material and the cutting edge dig into the material a sufficient depth to cut the desired shaving. 65 The operations of the oscillating or vibrating cutter with its pivotal cutting edge perform a very important function in cutting

the shaving. As shown in Fig. 5, the main portion *E*, or what might be termed the "shank" of the cutter, is provided with an 70 extending finger *e²*, and the cutter is made in the shape of a double right-angular triangle with a central recess, so that when it is swung one side or the other its inner edges *e⁴* will contact against this extending finger and prevent a further movement, the slight pivotal movement being necessary to remove one edge from cutting and permit the other edge to go into cutting engagement with the material. It will be noticed that the cutters are made 80 with a desired planing edge, so that they will not dig too roughly or deeply into the material, but just deep enough to cut a shaving of the desired thickness.

While I have described my invention with 85 more or less minuteness as regards details and as being embodied in certain precise forms, I do not desire to be limited thereto unduly or any more than is pointed out in the claims. On the contrary, I contemplate 90 all proper changes in form, construction, and arrangement, the omission of immaterial elements, and the substitution of equivalents as circumstances may suggest or necessity render expedient. 95

I claim—

1. In a machine of the class described, the combination of two reciprocating slides having racks thereon and arranged to hold projecting cutter portions in line with their motion, an oscillating-gear portion mounted between the same and engaging with the racks on the slide to impart the desired reciprocating motion, a pivotal tool-holder mounted independently and adjacent to the oscillating gear and provided with an extending-arm portion such holder being arranged to vibrate a cutter, and means for securing the vibrating-cutter-holder portion to the gear portion whereby the desired proportional motions are given such parts, substantially as described. 100

2. In a machine of the class described, the combination of two reciprocating slides having racks thereon and arranged to hold projecting cutter portions in line with their motion, an oscillating-gear portion mounted between the same and engaging with the racks on the slide to impart the desired reciprocating motion, a pivotal tool-holder mounted independently and adjacent to the oscillating gear and provided with an extending-arm portion such holder being arranged to vibrate a cutter at right angles to the movement of the slides, means for securing the vibrating-cutter-holder portion to the gear portion whereby 105 the desired proportional movements are given to such parts, means for holding the material, means for adjusting the material to the desired position, and means for feeding the material-holder with the material into contact 110 with the cutters, substantially as described. 115

3. In a machine of the class described, the combination of two reciprocating slides having racks thereon, cutter portions adjustably

secured to the rack-slides, an oscillating-gear portion mounted between the racks and engaging with the same so as to impart the desired reciprocating motion to the slides, a pivotal tool-holder mounted independently and adjacent to the oscillating gear and provided with an extending-arm portion, such holder being arranged to vibrate a cutter, and means

for adjustably securing the vibrating cutter-holder to the gear portion so as to obtain variable vibratory motions of the vibrating cutter, substantially as described.
